UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

BY-PASS-VALVE CONSTRUCTION.

Application filed September 22, 1921. Serial No. 502,542.

My invention relates to by-pass valves used to regulate the quantity of liquid supplied in liquid pumps, particularly of the type used in supplying fuel to injection engines.

5 The system here described is particularly designed for injection engines employing the so-called solid or direct injection system and in which the timing of the injection is controlled by the fuel pump. Where the timing 10 of the discharge from the fuel pump is of little or no importance as with an air injection system or a mechanically operated and timed injection valve, and also with some 15 types of engines employing hot bulbs or plates, the system here described is no advantage, but it is usually desirable and often necessary with direct injection and an automatic valve to maintain the timing of the injection into the cylinder fixed as to its commencement. 20 My device provides a valve needing but a very light operating mechanism which will permit the injection to begin always at the same point and which will later on in the pump stroke open and permit the 25 remainder of the fuel charge to be returned to the fuel supply system.

By-pass valves are used in fuel pumps which supply a fixed quantity of fuel for each stroke where it is desired to inject a varying 30 quantity of fuel corresponding to the load on the engine. Such by-pass valves are provided in order that the portion of the quantity pumped which is not required by the engine, may be returned to the fuel supply 35 system.

As generally known such by-pass valves have opened inward against the pressure in the pump chamber. Such inwardly opening valves must for obvious structural reasons be 40 of considerably larger diameter than outward opening valves, because the inward opening valve exposes a diameter at least equal to the larger seat diameter, and the smaller seat diameter must be large enough 45 to permit the passage of a substantial stem. Such valves are always of the poppet valve type. With an outward opening valve, however, only the smaller seat diameter is exposed, and this smaller seat diameter may be 50 considerably reduced in proportion to the other type, since no stem is required to pass through this area.

A further disadvantage of inward opening

valves is that they must be opened against the pressure in the pump chamber. Since the 55 surface of the valve is necessarily comparatively large as above explained, the total load upon it and consequently upon the operating mechanism will be very heavy. For example, with an injection pressure of 5,000 pounds 60 to the square inch and a valve having a major seat diameter of $\frac{3}{8}$ of an inch, the total load on the valve will be 550 pounds. It is obvious that a very heavy mechanism will be necessary to open such a valve inwardly in the 65 face of such a load. This difficulty is magnified by the fact that the opening of the by-pass valve is governor controlled and that somewhere in the linkage which operates the valve there is a variable member which controls the 70 quantities by-passed. This member is usually governor operated, and where this is the case the governor is necessarily very heavily loaded, even though there be reductions both in the valve operating mechanism and in the 75 linkage connecting the variable member with the governor. Since it is well recognized that the load on the governor should be kept as light as possible to avoid irregular and inaccurate action it is obvious that a mechanism 80 which places a heavy load on the governor is undesirable.

One of the objects of my invention is to free the governor as completely as possible from any load. With this end in view, I have provided an outwardly opening by-pass valve of the needle type. In my construction the valve is seated outside of the pressure chamber of the pump and only the small needle point is subjected to the pressure within the 90 pump. With an outwardly opening valve the minor seat diameter may be as small as usable oil velocities permit. A pump in which the inward opening type of valve is used might have a major seat diameter of $\frac{3}{8}$ of an inch 95 with reasonable design, whereas the outward opening valve for the same pump need only have a minor seat diameter of $\frac{1}{16}$ inch to permit free passage of the oil. With a diameter of $\frac{1}{16}$ of an inch and 5000 pound injection pressure, the load on the valve will be only 15 pounds in contrast to 550 pounds for the inward opening type.

My invention is illustrated more or less diagrammatically in the accompanying drawings, wherein—

Figure 1 is a vertical cross section;

Figure 2 is a plan view with parts in section;

Figure 3 is a cross section on line 3-3
5 of Fig. 1;

Figure 4 is an enlarged detail of the by-pass
valve.

Like parts are designated by like characters
throughout.

10 A is a pump housing enlarged at one end
as at A' and provided with the bore A² within
in which the slider B is adapted to recipro-
cate. This slider is hollow as at B' and is
closed at one end as shown. It is provided
15 at its closed end with the roller B² which is
pivoted therein. C is a cam shaft on end of
which extends into the hollow A' of the pump
housing A. Mounted on the cam shaft C is
the cam C' which is adapted to work against
20 the roller B². Adjacent the cam C' is the
eccentric C² about which is the eccentric
strap C³ which carries the ear C⁴ in which
is pivoted one end of the lever D, the other
end of which is pivoted in the housing at D'
25 as shown.

Within the bore B' of the slider B is fixed
the rod E which has at its inner end the
enlarged portion E'. Fixed about the rod E is
30 the retainer E² which is perforated as at E³
and has the enlargement E⁴ at its inner end.

F is the pump body fixed to the pump hous-
ing A and within it a liner F' is also fixed.
The spring E⁵ surrounds the retainer E² and
35 bears at one end upon the enlarged portion
E⁴ and at the other end upon the pump body.

G is a pump plunger adapted to recipro-
cate within the liner F' and extending
through the perforation E³ in the spring re-
tainer E². It has the enlarged head G' which
40 lies within the spring retainer and in contact
with the rod E. F² is a pump chamber within
the liner F'. Communicating with this
pump chamber is an inlet H which is nor-
mally closed by the valve H' which is opened
45 in opposition to the spring H² by the suc-
tion within the pump chamber. Commun-
icating also with the pump chamber is the
outlet I which is normally closed by the valve
I' which is adapted to be opened in opposi-
50 tion to the spring I² by pressure within the
pump chamber. When the valve is so
opened, fuel is discharged through the valve
and through the fuel line I³.

55 Communicating with the pump chamber
is the by-pass J adapted normally to be
closed by the by-pass valve J'. The valve
is normally seated by means of the spring J²
which surrounds the separated valve stem
J³. This stem has upon it the enlargement
60 J⁴ and is adapted at one end to slide within
the guide J⁵. The spring J² bears against
the enlargement J⁴ and the guide J⁵. The
valve stem J³ is separate from the valve and
is normally in contact with it. It is reduced
65 at its inner end as at J⁶, and surrounding this

reduced portion is a spring J⁷ which on the
suction stroke aids the prompt seating of the
valve irrespective of the position of the sepa-
rated valve stem.

Pivoted mid-way between the lever D is 70
the link K which is attached to the push rod
K'. This rod carries in its outer end the
wedge K². K³ is a second push rod which
carries in its inner end the block K⁴. At the
75 outer end of the push rod K³ is adjustably
fixed the bracket K⁵. K⁶ is the driving
spring about the shaft K³.

L is a rod connected by any suitable link-
age with the governor and adapted to be
moved in and out by the same. The details 80
of this construction are not here shown as
they form no part of the present invention.
Mounted on the end of the rod L is a wedge
L'. This wedge as shown is contacted by the
wedge K² of the block K⁴. In accordance 85
with its position as it is moved in and out by
the governor, the length of the linkage from
the lever D to the block K⁴ is varied and the
time at which the bracket K⁵ contacts with
the enlargement J⁴ is varied, thus changing 90
the time at which the valve J' opens and
varying the time in the pump stroke at which
discharge to the injection valve ceases and
discharge through the valve J' commences to
the fuel tank. 95

The use and operation of this invention are
as follows:

With the rotation of the cam shaft the push
rod is reciprocated, the total length of the
push rod linkage being varied by the move-
100 ment of the wedge which is controlled by the
governor.

The action of the push rod assembly is as
follows: During the outward reciprocation
of the two push rods, the bracket on the outer 105
one contacts the collar on the separated valve
stem and so moves it outward in opposition to
the spring which surrounds the valve stem.
This movement of the valve stem frees the
valve which is then forced from its seat by 110
the pressure in the pump chamber, the by-
pass being thereby opened. In the opening
of the valve the effect of the small spring
which surrounds the reduced portion of the
separated valve stem is negligible in oppo-
115 sition to the pressure from the pump cham-
ber upon the valve. As thus described the
opening of the valve is entirely mechanically
controlled but the closing which will now
be described, is purely automatic. 120

Practically the moment that the pump
plunger begins its return stroke, suction is
substituted for the pressure within the pump
chamber and this suction combined with the
action of the small spring bearing against 125
the valve in causing prompt closure imme-
diately upon the commencement of the suc-
tion stroke. Subsequent to the closing of the
valve the push rod assembly makes its return
reciprocation to the point where the larger 130

spring is enabled to return the valve stem to the position shown in Fig. 1, and the parts are returned to this position before any pressure is built up in the pump chamber. The 5 valve is then held closed against injection pressure by the larger spring, until the moment when the above described cycle is commenced again.

Since the valve itself is separate from the 10 comparatively large and heavy valve stem and other operating parts, and since the small valve is automatically seated before the return movement of the valve stem, and since the valve stem and other parts may by this 15 construction be returned gradually, prompt closing is accomplished without pounding and battering, resulting from the inertia of the heavy parts. If the valve were integral with the valve stem and positively connected 20 with the other parts of the valve operating mechanism to obtain quick closure of the valve, very rapid motion of the operating parts would be necessary, and this objectionable pounding on the seat would be greatly 25 increased.

I claim:

1. In combination with a pressure chamber and means for intermittently building up pressure therein, a discharge passage there- 30 from and a by-pass discharge therefrom, a closure for the by-pass normally held against opening, opening in response to pressure in the chamber, and means for intermittently releasing said closure to permit by-pass dis- 35 charge away from supply, and separate means for seating said by-pass valve.

2. In combination with a pressure chamber and means for intermittently building up pressure therein, a discharge passage there- 40 from, and a by-pass discharge therefrom, a closure for the by-pass normally held against opening, opening outward in response to pressure in the chamber, and means for re- 45 leasing said closure to permit intermittent by-pass discharge away from supply, said closure comprising a floating valve adapted to close automatically upon reduction of pressure in the chamber.

3. In combination with a pressure chamber 50 and means for intermittently building up pressure therein, a discharge passage there- from, and a by-pass discharge therefrom, a closure for the by-pass normally held against opening, opening outward in response to pres- 55 sure in the chamber, and means for releasing said closure to permit intermittent by-pass discharge away from supply, the by-pass valve being adapted to close automatically when the unbalanced forces tending toward 60 opening are reversed.

4. In combination with an internal com- busion engine, a liquid pump having a pres- 65 sure chamber, and a by-pass leading from said chamber, an outwardly opening valve held on its seat by a separate stem and being adapt- ed to close said by-pass and to open intermit- tently and automatically in response to pres- 70 sure from within the chamber, means for operating said valve including a reciprocating linkage eccentrically driven by said engine, a link of variable governor controlled length within said linkage.

5. In combination with an internal com- busion engine, a liquid pump having a pump 75 chamber with a by-pass therefrom, an out- wardly opening valve held on its seat by a separate stem and yielding means normally adapted to seat said valve and means for com- pressing said yielding means to permit said valve to be opened outwardly by pressure 80 within said pump chamber, said means comprising a reciprocating linkage eccentrically driven by said engine and having a link of vari- able length therein, said valve adapted to open intermittently and automatically in re- 85 sponse to pressure from within the chamber.

6. In a liquid pump, a pressure chamber, a by-pass in communication therewith having a valve therein, and yielding means for nor- 90 mally holding said valve seated, said means comprising a reciprocating valve stem sep- arate from and in contact with said valve, and a spring adapted normally to hold said stem against said valve to seat same, and means for positively moving said stem out of contact 95 with said valve whereby the valve is adapted to open automatically, and intermittently in response to pressure within the pressure chamber when the same is mechanically with- drawn.

7. In a liquid pump, a pressure chamber, a by-pass in communication therewith having a valve therein, and yielding means for nor- 100 mally holding said valve seated, said means comprising a reciprocating valve stem sep- arate from and in contact with said valve, and a spring adapted normally to hold said stem, against said valve to seat same, and means for positively moving said stem out of con- 105 tact with said valve, and a spring between said stem and said valve, said spring normally under pressure whereby the valve is adapt- ed to open automatically, and intermittently in response to pressure within the pressure chamber when the same is mechanically with- drawn.

Signed at Chicago, county of Cook and State of Illinois, this 20th day of September, 1921.

PHILIP LANE SCOTT.
